UNITED STATES PATENT OFFICE.

NORRIS C. LEONARD, OF BALTIMORE, MARYLAND.

DENTAL APPLIANCE.

Application filed October 15, 1925. Serial No. 62,572.

This invention relates to improvements in dental appliances and more particularly to means for the orthodontic treatment of mal-occlusion of teeth and stimulation to the 5 growth of the jaw and other undeveloped or malformed bones of the face,—one object of the invention being to provide means whereby the natural occlusal forces may be utilized to correct malocclusion.

10 A further object is to provide means to enhance positive intermaxillary force in making mesio-distal adjustments of the teeth, or in changing the mesio-distal relations of the maxillary and mandibular bones.

15 With these and other objects in view, the invention consists in certain features herein-after set forth and pointed out in the claims.

In the accompanying drawings:—

20 Figure 1 is a view showing my improvements applied to teeth of upper and lower jaws;

Figure 2 is a view in elevation;

Figures 3 and 4 are views of the devices; Figure 5 is a sectional view;

25 Figure 6 is a sectional view at right angles to Fig. 5;

Figure 7 is a view showing another embodiment of the invention.

The usual method heretofore practiced in 30 applying intermaxillary force for securing movements or adjustments of teeth in orthodontic treatment has been through the use of ligatures (usually elastics) attached to stationary hooks located mesially in one jaw 35 and distally in the other, the elastics exerting a constant pressure or force which is delivered equally to each jaw, though in opposite directions.

40 My improvements utilize the natural physiological muscular forces used in normal mastication, the direction of these forces being slightly changed or modified by artificial inclined planes acting either upon each other, or upon natural inclined planes of 45 cusps of the teeth as the grinding surfaces of opposing ones are brought into occlusion during the act of masticating the food. By slightly changing at intervals the relation of the occluding inclined planes carried by the 50 opposing jaws, the muscular forces which normally act at right angles to the plane of occlusion are partially re-directed by the shifted inclined planes so that a part of the forces are received at right angles to the 55 axes of the teeth, causing them to move in a direction parallel to the plane of occlusion.

These forces which have been changed in direction by the contact of the inclined planes are delivered equally to the teeth of the opposing jaws, though in opposite directions, acting reciprocally in causing the movement of the teeth and development of the bones.

60 In the embodiment of the invention shown in Figure 1, portions of the upper and lower teeth therein are represented at 2 and 3 and my improvements are shown as applied to several teeth of each jaw. It will be understood however, that the devices may be made for application to a single tooth of each jaw.

65 A plurality of connected bands, (forming a band frame 4) are shown as fitted to three teeth of one jaw and from one side of said band frame a plurality of prongs 5 depend. These prongs are preferably made somewhat 70 tapering and are rounded or beveled at their free ends so that they will present inclined planes 6 which cooperate with each other inclined planes carried by teeth of the other jaw (as hereinafter described) and thus operate when the jaws come together as in masticating, to move the teeth toward position for correct occlusion.

75 Connected bands, forming a band frame 7, are fitted to a plurality of teeth of the opposing jaw (the lower jaw in the embodiment of the invention shown in the drawing), and this band frame 7 has, assembled therewith, a bracket 8 having a groove 9 to receive an edge portion 10 of a movable 80 member 11 when the latter is disposed in operative position upon the bracket. The bracket 8 is also provided with sleeves 12 and 13, through which an adjusting screw 14 passes freely,—one end of said screw having a tool-receiving head 15 and having a nut 16 on its other end, so that longitudinal movement of said screw will be prevented. A sleeve 17 projects from the movable member 11 and enters between the bracket sleeves 100 12 and 13, said sleeve 17 being internally threaded for the accommodation of the adjusting screw 14 so that when the latter is turned, the member 11 will be moved longitudinally. The movable or adjustable member 11 is formed with a plurality of depressions 18 corresponding in number with the prongs 5 and adapted to receive the same. The walls of the depressions 18 are so beveled as to present inclined planes 19 with 105 which latter the prongs cooperate to cause movement of the member 11 and with it, the 110

bracket 8 and the teeth to which said bracket is attached by means of the band frame 7.

It will be understood that when the devices are first applied to teeth of a patient, the horizontal adjustment of the member 11 carried by teeth of one jaw, relatively to the prongs carried by teeth of the other jaw, will be comparatively slight, so that the teeth to be moved toward correct position will be slightly moved during mastication over a comparatively limited period of time. The movable member 11 may be moved or adjusted from time to time until the mal-occlusion shall have been fully corrected, and this without subjecting the patient to undue discomfort.

In the embodiment of the invention shown in Figure 7, a bracket 20 is fitted over a plurality of teeth of one jaw and on this bracket a movable member 21 is mounted to be slid or adjusted longitudinally over said bracket 20 and over the cusps of the teeth covered by the same. The movable member 21 is provided with an impression of the cusps of the teeth over which it is disposed, as indicated by the depressions 22, the walls of these depressions forming inclined planes with which teeth of the other jaw cooperate to effect correction of mal-occlusion. The movable member 21 may be adjusted by means of screw devices as indicated at 23.

Having fully described my invention what I claim as new and desire to secure by Letters-Patent, is:—

1. Orthodontic means, comprising a member to be carried by teeth of one jaw and having inclined planes to be engaged during masticating movements of the jaws to cause the upper and lower jaws or teeth to be moved respectively in opposite directions.

2. Orthodontic means, comprising a member to be carried by teeth of one jaw and having inclined planes to be engaged during masticating movements of the jaws to cause the upper and lower jaws or teeth to be moved respectively in opposite directions, and means to adjust said member in

a direction approximately at right angles to the longitudinal axes of the teeth.

3. Orthodontic means, comprising a support to be carried by teeth of one jaw, a member movably mounted on said support and having inclined planes to be engaged during mastication, and screw means for adjusting said member on said support longitudinally of the latter.

4. Orthodontic means, comprising a support adaptable for attachment to teeth of one jaw, a member mounted on and adjustable longitudinally with relation to said support, said member having depressions forming inclined planes, and means adaptable for attachment to teeth of the other jaw and cooperable with the inclined planes of said member.

5. Orthodontic means, comprising a support adaptable for attachment to teeth of one jaw, a member mounted on and adjustable longitudinally with relation to said support, said member having depressions forming inclined planes, and prongs adaptable for attachment to teeth of the other jaw and cooperable with the inclined planes of said member.

6. Orthodontic means, comprising a support adaptable for attachment to teeth of one jaw, a member mounted on and adjustable longitudinally with relation to said support, said member having depressions forming inclined planes, and prongs providing inclined planes adapted for attachment to teeth of the other jaw and cooperable with the inclined planes of said member.

7. Orthodontic means, comprising a bracket, means for attaching said bracket to teeth of one jaw, a member movably mounted on said bracket and having inclined planes to be engaged during mastication, a screw carried by said bracket and having threaded connection with said member whereby the latter may be adjusted longitudinally with relation to said bracket.

In testimony whereof, I have signed this specification.

NORRIS C. LEONARD.
